UNITED STATES PATENT OFFICE

JOSEPH BURNS, OF OKMULGEE, OKLAHOMA.

WIRE-LINE-ROPE SOCKET.

1,073,470.

Specification of Letters Patent. Patented Sept. 16, 1913.

Application filed April 8, 1913. Serial No. 759,754.

To all whom it may concern:

Be it known that I, JOSEPH BURNS, a citizen of the United States, and resident of Okmulgee, in the county of Okmulgee and State of Oklahoma, have invented certain new and useful Improvements in Wire-Line-Rope Sockets, of which the following is a specification.

One object of this invention is to provide an efficient swivel rope socket for well tools wherein the swivel is easily accessible and from which water and sand may readily clear.

A further object is to provide an improved abutment within the socket body for the lower end of the swivel head or mandrel; also to combine with such abutment a means for obstructing the opening of the body through which the swivel head is entered.

In the accompanying drawings, Figure 1 is an elevation of a rope socket constructed in accordance with the invention, and Fig. 2 is a vertical longitudinal section of the same. Fig. 3 is a sectional plan taken on line 3—3 of Fig. 2. Fig. 4 is a detail of the abutment-forming device entered in the socket body. Fig. 5 is an elevation, and Fig. 6 a vertical section similar to the upper portions of Figs. 1 and 2, respectively, illustrating an abutment-forming device of modified form. Fig. 7 is a detail of the modified abutment.

Referring to the drawings, 2 designates the body of the socket which is formed at its lower end with the usual threaded box 3 for receiving the tapered pin carried by the upper extremity of all socket-supported well tools. Body 2 is formed with the vertical cylindrical cavity 4 which for convenience of manufacture may consist of an upward extension of box 3, the cavity extending well up toward the upper end of the body and with a rope passage 5 extending from the upper end of the cavity through the upper extremity of the body. Cavity 4 and passage 5 are concentric with the longitudinal axis of the body and as the rope passage is smaller than the cavity the upper extremity of the latter forms the shoulder or abutment 6.

A portion of the length of cavity 4 is open laterally through the side of the socket body as indicated at 7, the upper end of this lateral opening being in a plane lower than abutment 6, and entered through open-

ing 7 is the cylindrical head or mandrel 8, which has a turning fit in cavity 4. Head 8 is formed with the upwardly tapering bore 9 to confine the knotted extremity 10 of cable 10, the latter extending into the socket body through passage 5. Part 8 is in effect a swivel head for the cable, the upper extremity thereof bearing against shoulder 6, with socket body 2 adapted to turn or swivel thereon, as will be understood.

Entered through lateral opening 7 is device 11 which fits cavity 4, said device being of plug form with the lower portion 11' thereof extending downwardly into cavity 4 beneath inlet passage 7. Lateral extension 12 of part 11 fits the lower portion of outlet passage 7 and so contracts the latter as to prevent swivel head 8 from lowering sufficiently to pass outwardly therethrough, the upper portion of passage 7 being spaced downwardly from abutment 6 so that bore 4 extends above said passage, as indicated at 4'.

Fitting a socket 13 in one side of part 11 is pin 14 which is held normally projected by spring 14', with the pin adapted to enter cavity 15 in the wall of bore 4, thus locking part 11 in position therein. Passage 15 is reduced in size and extended to the outer face of socket body 2, as indicated at 15', so that a set or like device may be introduced for retracting the pin when part 11 is to be released and removed.

The vertically movable swivel head or mandrel 8 may be utilized for jarring the socket, part 11 providing an effective abutment for receiving the down strokes, and as said part fits closely within the socket bore 95 the force of the blows is communicated through extension 12 to the socket body. The purpose of such jarring is well understood in the art, and need not be explained in detail.

In the adaptation shown in Figs. 5, 6 and 7, lateral extension 12 of the abutment-forming part 11 is formed with the upward horn-like extension 16 which substantially closes passage 7, there being sufficient clearance, however, as indicated at 17, between the side faces of said extension and the walls of the passage to permit sand and water to escape from the swivel chamber, so that the tool is self-cleaning as to any sand and water that may enter the swivel by passing downwardly along cable 10.

Claims for a rope socket provided with a cable anchorage or swivel head which is adapted to be entered and removed through a lateral opening in the socket body are 5 made in my copending application for Letters Patent filed February 7, 1913, Serial No. 746,812.

I claim:

1. The combination of a rope socket 10 adapted at its lower end to connect with well tools and at its upper end formed with a cable inlet passage, the body formed with a cavity beneath said passage with said cavity open laterally, a head within the 15 cavity and smaller than the lateral opening and adapted to pass therethrough and be secured to a cable entered through the cable passage, and means secured within the lateral opening for obstructing outward movement of the head.
2. The combination of a rope socket body 20 adapted at its lower end to connect with well tools and at its upper end formed with a cavity open laterally, a head within the 25 cavity and smaller than the lateral opening and adapted to pass therethrough, the upper portion of the body formed with a cable passage with the head adapted to be secured to a cable entered through the passage, and a device removably entered in the 30 body cavity and extending into and partially closing the lateral opening, said device limiting the downward movement of the head and preventing outward movement thereof through the lateral opening.
3. The combination of a rope socket body 35 adapted at its lower end to connect with well tools, the body formed with a laterally open swivel-head cavity and also open to admit a drilling cable, a swivel head within the cavity and secured to the cable extremity, the head being smaller than the lateral opening of the cavity and adapted to pass inwardly and outwardly therethrough, an 40 abutment device smaller than the lateral opening and adapted to pass inwardly and outwardly therethrough, said device having a plug-like portion fitting the body cavity beneath the laterally open portion thereof, 45 the abutment device having a side extension lying within and obstructing the lateral opening, the abutment device preventing removal of the swivel head, and means for removably securing the abutment device in 50 position.
4. The combination of a rope socket body 55

adapted at its lower end to connect with well tools and at its upper end formed with a cavity open laterally through a face of the body, a head adapted to be entered in the 60 cavity through the lateral opening, the upper portion of the body formed with a cable passage with the head adapted to be secured to a cable entered through the passage, an abutment-forming device within the body 65 cavity and adapted to be engaged by the head when in lowered position, and a normally projected spring-actuated pin carried by the abutment with a wall of the body cavity formed with an opening adapted to 70 receive the pin.

5. The combination of a rope socket adapted at its lower end to connect with well tools and at its upper end formed with a cavity open laterally through a face of 75 the body, a head adapted to be entered in the cavity through the lateral opening, the upper portion of the body formed with a cable passage with the head adapted to be secured to a cable entered through the passage, an abutment-forming device within the body cavity and adapted to be engaged by the head when in lowered position, and a normally projected spring-actuated pin carried by the abutment-forming head, the 80 body formed with a pin passage extending to its outer face which is adapted to receive the spring-projected pin and also adapted to form a passage for a pin-retracting device when the head is to be released.

6. The combination of a rope socket body 85 adapted at its lower end to connect with well tools, the body formed with a bore extending upwardly from its lower end and with the upper end of the body formed with a cable entering passage which communicates with the bore, the body formed with a lateral outlet passage communicating with the upper portion of the bore, a head adapted to be entered in the cavity through the 90 lateral opening and adapted to be secured to a cable, an abutment forming device extending downwardly into the bore beneath the lower end of the lateral passage, and an extension on said device lying within and 100 adapted to obstruct the lateral passage.

In testimony whereof I affix my signature in presence of two witnesses.

JOSEPH BURNS.
